UNITED STATES PATENT OFFICE.

JONAS NORTHRUP, OF HOPEDALE, MASSACHUSETTS, ASSIGNOR TO
DRAPER COMPANY, OF HOPEDALE, MASSACHUSETTS, A CORPO-
RATION OF MAINE.

FILLING-REPLENISHING LOOM.

SPECIFICATION forming part of Letters Patent No. 724,120, dated March 31, 1903.

Application filed January 5, 1903. Serial No. 137,924. (No model.)

To all whom it may concern:

Be it known that I, JONAS NORTHRUP, a subject of the King of Great Britain, and a resident of Hopedale, county of Worcester, State 5 of Massachusetts, have invented an Improvement in Filling-Replenishing Looms, of which the following description, in connection with the accompanying drawings, is a specification, like letters on the drawings representing like 10 parts.

This invention relates more particularly to looms wherein the running-shuttle is provided automatically with filling, as in United States Patent No. 529,940.

15 When a fresh supply of filling is inserted in the shuttle and the latter is shot across the lay, the filling end extends from the hopper or filling-feeder to the cloth, and to cut this filling end and prevent it from breaking and

20 weaving into the cloth a thread-cutter is provided, commonly mounted on the temple. In practice it has been found that very frequently this filling end will be struck by the inner end of the front box-wall on the beat- 25 up and will draw over the wall, and when the lay swings back the box-wall will again hit the filling end and slide beneath it. This sawing action is sometimes repeated so often that the filling end is broken before the thread- 30 cutter has severed it, as the cutter is not certain to sever the thread on the first beat-up after replenishment. Of course with such a breaking of the thread there is a great tendency to weave the end into the cloth, making 35 an imperfection. The front box wall or plate has been shortened or cut down to avoid rubbing the filling end; but this is objectionable, as insufficient support is left for the shuttle.

40 My present invention has for its object the production of simple means for preventing the filling end from drawing or sawing over the box-wall, as heretofore referred to, and it also serves to move the filling end into position to be parted by the thread-cutter.

45 The novel features of my invention will be described in the subjoined specification and particularly pointed out in the following claims.

Figure 1 is a front elevation of the replen-

ishing shuttle-box of an automatic loom with 50 one embodiment of my invention applied thereto. Fig. 2 is a top or plan view thereof, showing the temple thread-cutter, the position of the front box-wall of the shuttle-box when the lay is forward being shown in dotted lines; and Fig. 3 is a detail inner end view of the box-wall, showing the thread-engaging device thereon.

The lay A³, the replenishing shuttle-box B^X, and the temple T, provided with a thread-cutter c²⁰, are and may be substantially as shown and described in United States Patent No. 641,763, dated January 23, 1900, the filling-end holder b' (see dotted lines, Fig. 1) being the only part of the filling-feeder shown, said 60 feeder constituting a part of the automatic filling-replenishing mechanism, as will be manifest to those skilled in the art.

In the present embodiment of my invention the front box wall or plate B of the replenishing shuttle-box has the inner end of its overhanging top or flange b² shaped to present a forwardly-extended projection b³, the top of said projection being slightly above the top of the box-wall. (See Fig. 1.) The under face b⁴ of the projection is downwardly and rearwardly beveled, as best shown in Fig. 3, and terminates at the outer surface of the box-wall, the top or flange b² being preferably provided with a rounded notch b⁵ adjacent the 70 outer side of the projection. Beyond this notch the flange is chamfered or rounded, as at b⁶, for a purpose to be described. The filling end is shown at t, it being supposed that after transfer of filling the shuttle S has been 75 thrown across the lay from the box B^X and back again to said box, the filling end extending from the holding-plate b', Fig. 1, to the cloth.

In Figs. 1 and 2 the position of the filling 90 end relative to the front box-wall B is shown in full lines when the lay is back. As the lay beats up the projection b³ passes over and above the filling end, and the beveled face b⁴ of said projection, acting with the chamfered 95 portion b⁶ of the top b² of the box-wall, tends to push the filling end down beneath the part b⁷ of the top. This is shown in Fig. 2 in dotted

lines, the lay then being fully forward, and it will be seen that the filling end is drawn into the range of the temple thread-cutter to be severed thereby.

5 It is impossible for the filling end to draw across or saw over the top of the box-wall, because the beveled face b^4 of the projection b^3 acts to push it downward, and should the cutter fail to sever the filling end on the first forward beat of the lay the projection will again engage such filling end on the next beat and again present it to the cutter.

Manifestly the thread-engaging device will act upon the filling end, as described, upon the first beat-up after transfer of filling, the shuttle then being in the opposite shuttle-box.

Should the inclination of the filling end be greater than shown in Fig. 1, it might pass into the notch b^5 and under the projection b^3 and still be prevented from drawing over the top of the box-wall.

Having fully described my invention, what I claim as new, and desire to secure by Letters Patent, is—

25 1. In a loom provided with automatic filling-replenishing mechanism, a shuttle-box, and a device on the front wall thereof having its front edge arranged to engage the fresh filling end on the beat-up after replenishment 30 and prevent it from rising and sawing over the box-wall as the shuttle-box moves back and forth.

2. In a loom provided with automatic filling-replenishing mechanism, a thread-cutter 35 located adjacent the edge of the cloth, a shuttle-box, and a device on the front wall thereof, to engage the fresh filling end on the beat-up after replenishment and carry it into range of the cutter and also acting to prevent the 40 filling end from rising or sawing over the box-wall as the shuttle-box moves back and forth.

3. In a loom provided with automatic fill-

ing-replenishing mechanism, including a filling-feeder, a temple thread-cutter, a shuttle-box, and a thread-engaging device thereon to 45 engage the fresh filling end between the filling-feeder and thread-cutter on the beat-up and thereby direct said filling end to the cutter and also prevent it from rising over the shuttle-box.

4. A lay, a shuttle-box thereon, and a forwardly-extended projection thereon having a downwardly and rearwardly beveled under face to engage the filling end on the beat-up of the lay and prevent it from rising and drawing over the top of the shuttle-box.

5. A lay, a shuttle-box thereon, and a forwardly-extended projection on the front wall of the shuttle-box, near its inner end, to engage and pass over the filling end on the beat-up of the lay and prevent it from rising and drawing over the top of the box-wall.

6. A lay, a shuttle-box thereon, the front wall of which has an overhanging top, and a forwardly-extended projection thereon near 65 the inner end of the wall, the said projection having a downwardly and rearwardly beveled under face and the overhanging top being chamfered beyond said projection, the beveled face of said projection engaging and depressing the filling end on the beat-up of the lay, and causing such filling end to draw over the chamfered part of the overhanging top of the wall, to prevent the filling end from rising and sawing back and forth over the wall 70 as the lay swings back and forth.

In testimony whereof I have signed my name to this specification in the presence of two subscribing witnesses.

JONAS NORTHRUP.
